UNITED STATES PATENT OFFICE.

ERVIN E. SMITH, OF CANTON, OHIO.

DESIGN FOR A HIGHWAY DANGER SIGNAL.

Application filed August 17, 1926. Serial No. 18,770. Term of patent 7 years.

To all whom it may concern:

Be it known that I, ERVIN E. SMITH, a citizen of the United States, residing at Canton, in the county of Stark and State of Ohio, have invented a new, original, and ornamental Design for Highway Danger Signals, of which the following is a specification, reference being had to the accompanying drawing, forming part hereof.

Figure 1 is a front elevation of a highway danger signal, showing my new design, and Fig. 2, an edge elevation of the highway danger signal.

I claim:

The ornamental design for a highway danger signal, as shown.

ERVIN E. SMITH.
